ELIJAH BORTON, OF MORRIS, ILLINOIS.

Letters Patent No. 73,771, dated January 28, 1868.

IMPROVED DEVICE FOR OPERATING PUMPS.

The Schedule referred to in these Letters Patent and making part of the same.

TO ALL WHOM IT MAY CONCERN:

Be it known that I, ELIJAH BORTON, of Morris, in the county of Grundy, and State of Illinois, have invented a new and useful Improvement in Pump-Levers; and I do hereby declare that the following is a full, clear, and exact description thereof, which will enable others skilled in the art to make and use the same, reference being had to the accompanying drawings, forming part of this specification.

This invention relates to a new and improved method of operating the pistons or buckets of hand-pumps; and the invention consists in operating the pump by a cogged eccentric lever which engages with cogged segments, which also act eccentrically upon their centres, thereby imparting the required motion to the pump-rod, as will be hereinafter more fully described.

Figure 1 represents a side elevation of the pump, and

Figure 2 is a vertical section of the same through the line *xx*.

Similar letters of reference indicate corresponding parts.

A represents the pump. B represents the frame by which the segments and lever are supported, and also which support the guides for the pump-rod. C is the pump-rod. D is the lever. E is a segment which is attached to the pump-rod by a pivot, *a*, through an arm. F is another segment which is supported by the bed-piece of the frame, where it oscillates as upon a centre at *b*. The lever D has two semicircular gears attached to opposite sides of it eccentrically, as seen in the drawing. The pump-rod is attached to the segment E by the pivot *a*, through an arm, G, seen in fig. 1. The pump-rod C is supported and guided by the bracket H and by the projecting cap-piece of the frame, as seen at J.

It will be seen that the cogged segments E and F, as well as the segments on the lever, are eccentrics, and that by depressing the lever D, as seen in the drawing, the segment E will be raised a distance corresponding with the combined throw of all the eccentrics. The pump-rod C being connected with E, will of course be raised the same distance. The lever D turns on the pin *f*, which works up and down in the slot *i* in the uprights of the frame, as seen in the drawing. The inner standard of the frame B' is slotted for the purpose of allowing the arrow G to move the full stroke given by the lever. In actual use, the pump-rod and the segment E, with the water above the bucket or valve in the pump, will be of sufficient weight to keep the segment in contact with the eccentric on the lever.

By this arrangement it is seen that a much greater movement of the pump-valve is produced than can be by the lever-purchase of ordinary pumps.

Having thus described my invention, what I claim as new, and desire to secure by Letters Patent, is—

The eccentric segment F supported at *b* upon the bed-piece B, the eccentric semicircular gears upon the lever D sliding vertically in the slot *i*, the upper eccentric segment E sliding vertically in the slotted frame B', and pivoted to the arm G carrying the pump-rod C, all constructed and arranged to operate as herein shown and described.

ELIJAH BORTON.
